UNITED STATES PATENT OFFICE.

WILLIAM M. DOUGLAS, OF GALVESTON, TEXAS.

AUTOMATIC GUN OR RIFLE.

1,025,132.

Specification of Letters Patent.

Patented May 7, 1912.

Application filed June 30, 1911. Serial No. 636,248.

To all whom it may concern:

Be it known that I, WILLIAM M. DOUGLAS, a citizen of the United States, residing at Galveston, in the county of Galveston and State of Texas, have invented certain new and useful Improvements in Automatic Guns or Rifles, of which the following is a specification.

This invention relates to fire arms and has particular reference to an automatic gun or rifle.

An important object of this invention is to provide a magazine gun or rifle, which is automatically operated to eject the fired cartridges and reloaded, by utilizing a portion of the pressure from the exploding shell or cartridge.

A further object of this invention is to provide a gun or rifle of the above mentioned character, which is quick in action, easy and automatic in operation, and not liable to derangements.

Other objects and advantages of this invention will be apparent during the course of the following description.

In the accompanying drawings forming a part of this specification and in which like numerals are employed to designate like parts throughout the same, Figure 1 is a longitudinal sectional view taken through the magazine and associated members, Fig. 2 is a plan view of that portion of the gun or rifle shown in Fig. 1, Fig. 3 is a side view of the outer end of the barrel of the gun or rifle, shown partly in section, together with associated members shown in section, Fig. 4 is a side view of the gas-plunger, Fig. 5 is a cross-sectional view taken on line 5—5 of Fig. 3, Fig. 6 is a longitudinal sectional view taken through the air compressing cylinder, Fig. 7 is a longitudinal sectional view taken through the breech-bolt and associated members, Fig. 8 is a fragmentary side view of the stock of the gun or rifle, showing the hammer, magazine and associated members, Fig. 9 is a transverse sectional view taken on line 9—9 of Fig. 8, Fig. 10 is a longitudinal sectional view taken through the rear portion of the stock and showing the breech-bolt operating cylinder and associated members, Fig. 11 is a transverse sectional view taken on line 11—11 of Fig. 2, Fig. 12 is an end view of the breech-bolt, removed, and, Fig. 13 is a detail showing the ejector.

In the drawings wherein is illustrated a

preferred embodiment of my invention, the numeral 1 designates the barrel of the gun or rifle, which is disposed upon a forearm 2 of the usual stock. The barrel 1 is attached to the fore arm by bands 3 and 4, shown in Figs. 3 and 6. At the outer end the barrel 1 carries a sight 5 and a sword-bayonet 6 is secured to the outer end of the barrel 1 in the usual manner. Extending longitudinally through the forearm 2 is a gas-pipe or cylinder 7, having communication with the barrel 1 through a port 8, which is disposed near and spaced from the outer end of the barrel. A sleeve 9 connects the gas pipe 7 and the barrel 1, the port 8 passing through a portion of this sleeve. The outer end of the gas-pipe 7 is internally screw-threaded for receiving an externally screw-threaded plug 10, which is locked against rotation by a cap 11 having screw-threaded engagement therewith and with an extension formed upon the outer end of the gas-pipe 7. Disposed within the forward portion of the gas-pipe 7 is a gas-plunger 12 adapted to reciprocate therein and provided upon its periphery with annular grooves for receiving packing rings 13. The gas-plunger 12 has one end formed closed and is provided with an axial opening 14 which extends through the opposite end of the plunger. The gas-pipe 7 extends rearwardly through the forearm 2 and terminates near the rear band 4, as shown in Fig. 6. The rear end of the gas-pipe fits within or telescopes an air compressing cylinder 15, within which is mounted to reciprocate an air compressing piston 16, having annular grooves formed upon its periphery for receiving packing rings 17. A cylinder 18 is interposed between the gas-pipe 7 and the air compressing piston 16 and is rigidly held against movement. The cylinder 18 is provided centrally thereof with an opening for receiving a reciprocatory rigid rod 19, having its rear end attached to the air compressing piston 16 and its forward end attached to the gas-piston 12. A compressible coil spring 20 surrounds the rod 19 and is confined between the gas-piston 12 and the stationary cylinder 18. At the rear end of the air compressing cylinder 15 is a reducing pipe or conduit 21, having connection with two branch pipes or conduits 22 and 23. The pipe 22 continues longitudinally of the forearm and leads into the

forward end of a breech bolt cylinder 24, as more clearly shown in Figs. 10 and 2. The branch pipe 23 extends transversely of the forearm 2 and leads into a compressed air pipe 25, which is disposed upon the right side of the barrel 1, see Figs. 6 and 2. Connected with the rear end of the compressed air pipe 25 is an upstanding nozzle 26, as more clearly shown in Fig. 9. Disposed 5 within the breech-bolt cylinder 24 is a piston 27, slidably mounted therein and carrying a curved arm 28, which operates within an elongated slot 29. The rearward movement of the piston 27 is opposed by a compressible coil spring 30 disposed within the breech-bolt cylinder 24 and held therein by a plug or cap 31 which closes the rear end of the cylinder 29. The plug or cap 31 has screw-threaded engagement with the cylinder 24 and is clamped or locked against accidental rotation by a locking ring 32, having screw-threaded engagement with the cylinder 24, as shown in Fig. 10.

The numeral 33 designates a magazine for holding a plurality of shells or cartridges 34 in superposed horizontal positions. A spring 35 placed in the bottom of the magazine serves to move the cartridges upwardly, when the gun or rifle is being reloaded. Disposed above the magazine 33 is a sliding breech-bolt 36, disposed within a track or housing comprising side walls 37. The upper side of this housing is normally closed by a slide cover 38. The arm 28 operates 10 within a longitudinal opening 29 and is rigidly attached to the breech-bolt 36. This breech-bolt is preferably formed square in cross-section and is provided with a cylindrical axial opening formed therein for receiving a locking-cylinder 40. This locking-cylinder is capable of turning within the breech-bolt 36 but cannot have any perceptible longitudinal movement therein. As shown in Fig. 7, the locking cylinder 40 is 15 provided with a longitudinal opening 41 for receiving a firing pin 42 extending into a larger longitudinal opening 43 formed through the locking cylinder. Mounted to reciprocate within the opening 43 is a plunger 44 attached to the firing pin 42 and carrying a stop 45, disposed for movement within a slot 46. Surrounding a portion of the firing pin 42 is a compressible coil spring 46' confined between the end wall of the 20 opening 43 and one end of the plunger 44. The locking cylinder 40 is provided at one end with an enlarged cylindrical head 47, carrying interrupted screw-threads 48 upon its periphery, adapted for detachable engagement with corresponding screw-threads 49 formed on the wall of the bore of the barrel 1 and at the rear end of the barrel, as clearly shown in Figs. 1 and 2. The breech-bolt has an extractor 50 rigidly attached to the forward end thereof, which is 25

adapted to engage the flange 51 of a cartridge 52. The bore of the barrel 1 is counter-bored slightly, as shown at 53 to receive the cartridge.

The breech-bolt 36 is provided near its forward end and upon its upper face with a transverse opening 54, for receiving a downwardly curved handle-bar 55 which is rigidly connected with the locking cylinder 40. This handle-bar 55 is adapted to travel within a longitudinal slot 56 when moved vertically out of an enlargement 57, which is disposed at the forward end of the slot 56. The curved handle-bar 55 when the breech-bolt 36 is in its most forward position, is disposed directly above the compressed air nozzle 26. A leaf-spring 58 is attached to the breech-bolt and permanently engages the handle-bar 55 to swing the same downwardly. The housing is provided near its upper edge with a discharge opening 59 and upon its opposite wall with a pivoted ejector 60, which is automatically moved by a spring 61.

Disposed to the rear of the magazine is 90 a hammer 62 pivoted as shown at 63 in the small of the stock and adapted to strike the plunger 44. This hammer is operated by a main spring 64 and is normally held against movement by a trigger 65, pivoted 95 as shown at 66 and engaged by a trigger-spring 67. A pivoted cap 68 is adapted to be swung between the plunger 44 and the hammer 63, to avoid accidents.

The numeral 69 designates a trigger-guard and the numeral 70 designates a rear sight, which may be of any well known or preferred type.

In the operation of my gun or rifle, assuming that the same is loaded and that the 105 different parts occupy the position shown in Fig. 1, the operator cocks the hammer 62 and swings cap 68 from between the hammer and the plunger 44. When the trigger is pulled the hammer strikes the 110 plunger 44 and the cartridge 52 is fired. When the bullet of the cartridge passes port 8 and before it leaves the barrel 1, the gases under high pressure from the explosion pass through said port 8 into the gas cylinder 7. The gas-piston 12 is now moved rearwardly carrying with it the rod 19, which moves the air compressing plunger 16 rearwardly. By forming the gas-piston 12 with the axial opening 14 the gases pass 115 into such axial opening and expand the cylinder 12 whereby it always fits very snugly within the cylinder 7 and hence the gas can not pass the same. The air is now compressed within the cylinder 15 and part of 120 this compressed air travels through the pipe 22 and the other part through pipe 23 and into pipe 25. The compressed air is now 125 discharged from the nozzle 26 and by impacting against the handle-bar 55 elevates the 130

same out of the enlargement 57 of the slot 56. This movement of the handle-bar turns the locking-cylinder 40, whereby its screw-threaded head 47 disengages screw-threads

5 49. As soon as the locking-cylinder 40 is thus released, the compressed air acting upon the piston 27 will move the same to the rear, whereby the breech-bolt 36 is also moved to the rear. The breech-bolt by 10 means of the extractor 50 carries the fired cartridge 52 to the rear and positions the same opposite the discharge opening 59, at which time the automatic ejector 60 operates to throw the fired cartridge 52 out of 15 the magazine through the opening 59. In its rearward movement the breech-bolt 36 cocks the hammer 62. As soon as the fired cartridge 52 is discharged from the magazine, spring 35 will elevate the cartridges 20 to position the uppermost one forwardly of and in alinement with the breech-bolt 36. When the breech-bolt is moved forwardly and returned to the position shown in Fig. 1, it forces the uppermost cartridge 34 into the counter-bore 53 and hence the 25 gun is reloaded. This forward movement of the breech-bolt 36 is permitted by the decrease in pressure in the cylinder 24, which takes place after the bullet has left 30 the barrel 1, when the spring 30 forces the piston 27 forwardly, which through the medium of the arm 28 returns the breech-bolt 36 to its most forward position. As soon as the breech-bolt 36 is thus returned to its 35 forward position, the handle-bar 55 will be disposed in alinement with the enlargement 57, at which time the spring 58 will automatically swing the handle-bar downwardly, whereby the locking cylinder 40 is 40 turned and its screw-threads 48 brought into holding engagement with the screw-threads 49. When the operator again pulls the trigger the above described operation is repeated.

45 I have found that particularly good results can be obtained by employing cartridges having bullets provided with axial openings formed therein, in order that the gases from the explosion may enter the bullet and expand the same in the same manner as described in connection with my gas-piston 12. This will slightly retard the movement of the bullet in the barrel 1 and hence increase the pressure in the barrel and 50 55 the supply of such pressure through the port 8. I do not wish to restrict myself to the employment of such cartridges as my gun operates satisfactorily with the ordinary cartridge having a solid bullet.

60 I wish it understood that the form of my invention herewith shown and described is to be taken as a preferred example of the same and that certain changes in the shape, size and arrangement of parts may be 65 sorted to without departing from the spirit

of the invention or the scope of the subjoined claims.

Having thus described my invention, I claim:

1. In a fire arm of the character described, a barrel, a magazine for holding a plurality of cartridges to be fed into the barrel, a breech-bolt, an element to lock the breech-bolt in its closed position, compressed air operated means to actuate the element to release the breech-bolt, compressed air operated means to move the breech-bolt after it is unlocked, air compressing mechanism to supply compressed air to the first and second named compressed air operated means, a gas-cylinder having communication with the barrel and receiving gas therefrom on discharge, a gas-piston operating in the gas-cylinder and actuating said air compressing mechanism, means to return the breech-bolt to its closed position, 70 means to return said element to its normal position, and a device to move the cartridges so that they are successively placed in loading position. 75

2. In a fire arm of the character described, a barrel, a gas-cylinder having communication with the barrel and receiving gas therefrom on discharge, a piston operating within the gas-cylinder, an air compressing cylinder, a plunger operating within said air compressing cylinder, means connecting the piston and plunger, a breech-bolt carrying an extractor and coöperating with the barrel, an element for locking the breech-bolt in its closed position, mechanism actuated by compressed air from the air compressing cylinder for operating said element, and means actuated by such compressed air for moving the breech-bolt after 90 95 the same is unlocked. 100

3. In a fire arm of the character described, a barrel, a gas cylinder having communication with the barrel and receiving gas therefrom on discharge, a piston operating within the gas-cylinder, air compressing mechanism operated by said piston, a breech-bolt, an arm connected with the breech-bolt and carrying a piston, a cylinder within which the last named piston 110 115 operates, means of communication between said air compressing mechanism and the last named cylinder, a spring disposed within said last named cylinder to oppose the movement of the piston carried by the arm, 120 an element to lock the breech-bolt in its closed position, and mechanism actuated by compressed air from the air compressing means to operate said element. 125

4. In a fire arm of the character described, a barrel, a gas-cylinder having communication therewith to receive gas therefrom on discharge, a piston operating within the gas-cylinder, air compressing mechanism operated by said piston, a breech-bolt, 130

4
a locking cylinder mounted within the breech-bolt, an element to turn the locking cylinder, means to move the element, mechanism to move the breech-bolt after the same is unlocked, and conduits for supplying compressed air from said air compressing mechanism to said means and second named mechanism.

5. In a fire arm of the character described, a barrel, a gas-cylinder having communication therewith and receiving gas therefrom on discharge, a piston operating within the gas-cylinder, an air compressing cylinder, a plunger operating therein, a rod 10 connecting the piston and plunger, a spring to return the piston to its normal position, a breech-bolt, an arm connected with the breech-bolt and carrying a piston, a cylinder within which the arm piston operates, a 15 spring to return the arm piston to its normal position, means of communication between the air compressing cylinder and the last named cylinder, a locking element for normally holding the breech-bolt in its closed 20 position, a nozzle for conducting air to move the locking element, and means of communication between the nozzle and said air compressing cylinder.

6. In a fire arm of the character described, a barrel, a breech-bolt carrying an extractor and coöperating therewith, a locking element to hold the breech-bolt against movement and carrying a handle bar, a 30 nozzle disposed near the handle bar, and

means to supply compressed air to the 35 nozzle.

7. In a fire arm of the character described, a barrel, a breech-bolt carrying an extractor and coöperating therewith, a locking element to hold the breech-bolt against movement and carrying a handle bar, a 40 nozzle disposed near the handle bar, means for moving the breech-bolt including a cylinder and piston operating therein, and means for supplying the compressed air to 45 the nozzle and said cylinder.

8. In a fire arm of the character described, a barrel, a reciprocatory breech-bolt disposed near the loading end of the barrel and provided with an extractor, an element to normally lock the breech-bolt in its closed position, means to operate the element to release the breech-bolt, air compressing mechanism operated upon the discharge of the fire-arm, means of communication between the first named means and said mechanism, means including a piston to move the breech-bolt after it is released and operated by the air compressing mechanism, and means for firing the cartridge including an element disposed to be automatically cocked 50 by the movement of the breech-bolt.

55 In testimony whereof I affix my signature in presence of two witnesses.

WILLIAM M. DOUGLAS
